UNITED STATES PATENT OFFICE.

LEON L. BEAN, OF FREEPORT, MAINE.

TONGUE AND TOP REINFORCEMENT FOR SHOES.

1,373,399.

Specification of Letters Patent.

Patented Apr. 5, 1921.

Application filed June 11, 1920. Serial No. 388,294.

To all whom it may concern:

Be it known that I, LEON L. BEAN, a citizen of the United States, residing at Freeport, in the county of Cumberland and State 5 of Maine, have invented certain new and useful Improvements in Tongue and Top Reinforcements for Shoes, of which the following is a specification.

The present invention relates to the construction of boots and shoes and more particularly that type of shoe having the sole and vamp constructed of rubber and having a top made of leather or some such material.

An object of the present invention is to provide an improved top structure which is made waterproof at the points where the tongue is secured to the vamp and between the side pieces of the top.

Another object is to provide an upper construction wherein chafing and breaking of the threads is reduced to a minimum and practically eliminated.

Another object of the invention is to provide a shoe of the tongue variety wherein is eliminated the excessive wear on the lower end of the tongue where it is stitched or otherwise secured to the vamp of the shoe, the tongues of shoes of necessity being of relatively thin material to permit the bunching or gathering together of the tongue as the shoe is laced and tightened, the novel construction admitting of this gathering together of the tongue and at the same time preventing the undue wear and wrinkling of the lower end of the tongue.

A still further object of the invention is to provide an attachment or reinforcement of the tongue which is adapted to protect the lower end of the tongue and to protect the stitching by means of which the tongue is attached to the upper.

The above, and various other objects and advantages of this invention will be in part described in, and in part understood from, 45 the following detailed description of the present preferred embodiment, the same being illustrated in the accompanying drawing, wherein—

Figure 1 is a perspective view of a shoe 50 having the improvement of this invention applied thereto.

Fig. 2 is a transverse section through the lower end of the tongue and the adjacent

parts of the shoe to which the tongue is attached.

Fig. 3 is a plan view of the lower end of 55 the tongue with the attachment of this invention applied thereto.

Referring to the drawing, 10 designates the sole of a shoe and 11 the vamp thereof 60 which may be constructed in any suitable manner and of any desired material. In the present instance the invention is shown as applied to a hunting shoe wherein the sole 10 and vamp 11 are integral and made of 65 rubber.

The upper of the shoe is constructed in the usual manner of side pieces 12 and 13 of leather or the like which are secured at their lower edge portions by lines of stitching 14 70 to the vamp 11 and which are joined at the back of the shoe by a back stay 15.

The forward edge portions of the side pieces 12 and 13 are divided by lines of reinforcing stitching 16 into strips 17 adapted 75 to receive eyelets or the like through which laces or other fastening means may be secured for drawing together the front of the shoe top.

In the construction of shoe shown a tongue 80 19 is provided which is of less thickness than the side pieces 12 and 13 of the top and which is adapted to be gathered or bunched in between the edge strips 17 of the top when the latter is closed by the laces. The 85 tongue 19 is secured to the top by the lines of stitching 16 and the edges of the tongue constitute reinforcements or layers for increasing the strength of the strips 17 and receive the eyelets 18 therethrough. In this 90 manner the tongue 19 is secured to the shoe top.

The lower portion of the tongue is secured by continuations of the rows of stitches 14 which extend across the forward part of the 95 vamp 11 and which stitch the lower end of the tongue to the vamp. The strips 17 of the top terminate above the rows of stitches 14, as clearly shown in Fig. 1, and the tongue extends downwardly between the lower ends 100 of the strips 17 where it is secured to the vamp 11. For the purpose of reinforcing the tongue and carrying out the various other objects of this invention, a reinforcing piece 20 is stitched to the outer side of the 105 tongue 19 at the bottom thereof, and in plan

is substantially triangular in shape and is secured to the tongue with the apex or point thereof directed upwardly so as to provide a substantially V-shaped reinforcement which 5 decreases in width toward its upper end.

The lower end of the reinforcing piece 20 extends beyond the strips 17 of the top and is provided with laterally extending ears or 10 projections 21 adapted to fit snugly beneath the lower ends of the strips 17 and to be engaged by the rows of stitching 14 and secured thereby against the outer sides of the sections 12 and 13 of the upper.

The piece 20 is preferably of relatively 15 heavy material, and may be made of the same material as are the sections 12 and 13. The lower end of the tongue is exposed, and by providing the reinforcing strip 20 of the same material as the shoe top, the tongue 20 will conform in color and general appearance to the remainder of the shoe top as well as lending strength and rigidity to the lower end of the tongue whereby the stitches 14 will be protected and a neat closing of the 25 shoe may be effected.

The tongue proper, 19, may be of any suitable material and may be of any desired color as the tongue 19 is not visible when the shoe is drawn tightly into closed position 30 so that the only exposed part of the tongue is the reinforcing piece 20. The reinforcing piece 20, being of upwardly tapering form, admits of the ready gathering together of the side portions of the tongue 19 so that the shoe may be easily closed without interference and at the same time the lower part of the tongue will be held smooth 35 and from breaking away from the vamp 11. The ears or projections 21, in overlapping the side sections or parts 12 and 13, seal the lower end of the tongue to the vamp and sides and prevent the working in of snow and moisture, so as to provide a shoe 40 top which is substantially sealed and which 45 keeps the foot dry and warm.

The advantages of the reinforcing piece 20 are apparent for a less expensive tongue 50 may be used to properly fulfil the function required, and the tongue 19 may be made of any suitable material other than the material from which the shoe top is made. The reinforcing piece also holds the front of the shoe top flat and seals it effectively against moisture.

The laterally extending ears of the reinforcement also serve as means for strengthening the forward edges of the top to prevent the same from pulling away from the

vamp and also from wrinkling and chafing the stitching between the vamp, the top and 60 the tongue.

It is, of course, understood that various changes and modifications may be made in the details of construction and design of the above specifically described embodiment of 65 the invention without departing from the spirit thereof, such changes and modifications being restricted only by the scope of the following claims.

What is claimed is:

1. In a shoe, the combination with a 70 vamp, sides, and a tongue, of a reinforcing piece having lateral ears, said piece stitched to the bottom of said tongue and vamp, the lateral ears overlying the sides and stitched thereto, to permit the forward ends of said sides to overlie the tongue throughout its length.

2. In a shoe, the combination with a 75 vamp, a top and a tongue, of a reinforcing piece secured over the lower end of the tongue and tapering upwardly to hold the lower end of the tongue flat when the forward edges of the top are drawn together, said reinforcing piece having at its lower 80 end laterally extending ears secured beneath the forward edges of the top and stitched thereto with the top to said shoe vamp.

3. In a shoe, the combination with a 85 vamp, a top and a tongue secured at its 90 lateral edges to the forward edges of the top and at its lower end secured with the top to the edge of the vamp, of a reinforcing piece of substantially triangular form secured over the lower end of the tongue by 95 said stitches and tapering upwardly to hold the lower end of the tongue flat when the forward edges of the top are drawn together, said reinforcing piece having lateral 100 extensions secured by said stitches beneath the forward edges of the top and against the outer side of the latter whereby to seal the reinforcing piece against the forward portion of the top.

4. In a shoe, the combination with a 105 vamp, a top stitched thereto, and a tongue arranged between the forward edges of the top and stitched at its lower end to the 110 vamp, of a reinforcing piece secured by said stitches over the forward face of the tongue and extending laterally beneath the forward edges of the top and having laterally extending ears projecting beneath said forward edges of the top and secured by said stitches against the outer side of the top.

LEON L. BEAN.
